LEO HAUBERT, OF TULSA, OKLAHOMA, ASSIGNOR OF ONE-EIGHTH TO LYMAN LEROY ROLLER, OF TULSA, OKLAHOMA

LOAD BINDER

Application filed December 19, 1927. Serial No. 241,123.

This invention relates to load binders of that class usually employed for holding loads of logs or the like on cars or trucks, etc., and aims, among other objects, to provide improved readily operable and releasable means for use in connection with a binding chain, whereby the latter may be tightened around the load, while one end of the chain is constantly held by the device and new bites or holds are taken and held as the device is operated to secure the maximum tightness to the chain.

The invention is an improvement on the load binder disclosed in my pending application filed April 14, 1927, and bearing Serial No. 183,863.

In the accompanying drawing, wherein I have shown the preferred embodiment of the invention:—

20 Fig. 1 is a perspective view of the binder in position for taking up the slack in a chain.

Fig. 2 is a fragmentary view, partly in section showing the position of the parts when a new bite or hold is to be taken.

25 Fig. 3 is a sectional view taken on the line 3—3 of Fig. 2.

Fig. 4 is a detail view, similar to Fig. 3, showing the means for securing certain of the parts together.

30 Fig. 5 is a detail view of the chain-engaging means.

Referring particularly to Fig. 1 of the drawing, the binder, there shown, comprises an operating handle 1, preferably formed of 35 welded metal capable of withstanding the excessive strains to which the implement is subjected while in use. The handle is provided with an angularly formed active end 2 constituting an enlargement having a bifurcation 3 which thus provides a pair of spaced, forwardly-extending arms 4 having great strength and rigidity.

A pull rod 5 having a terminal eye 6 is pivoted within the bifurcation 3 adjacent to the 45 inner ends of the arms 4, said eye being mounted on a pin 7 having its ends seated in the arms at a point somewhat removed from the longitudinal axis of the operating handle 1. The upper end of the pull rod 5 is provided with a conical head 8 forming a swivel

connection with a tapered sleeve 9 having up-standing arms 10, the ends of which are brought together to form an eye 11 in which a link 12 is free to move. The other end of the link is connected to the eye of a hook 13 which may be employed in the usual manner, at times, if desired, by inserting the bill of the hook into the link of a chain, where it is not necessary to take new holds or bites on the latter for taking up slack.

55 The improved load binder is, however, designed to be used for taking up more slack in a chain than could be taken care of by a single movement of the operating handle and where the hook 13 would be used in the ordinary manner as stated above without the necessity for disengaging the same from the chain while the latter is under tension. For this purpose the hook 13 is provided with a

60 pair of spaced fingers 14 extending from one face thereof and at right angles to the same, the inner opposed faces of the fingers being oppositely concaved, as clearly shown in Fig. 5 of the drawing, to receive the rounded end 65 of a link of a chain 15 when the next adjacent link is fitted between the fingers. The fingers are slightly curved downwardly toward their outer ends to cause the chain to hug in toward the bases of the fingers to prevent accidental displacement of the chain connection.

70 Trunnions 16, preferably of integral formation with the spaced arms 4 of the operating handle, extend outwardly in alinement with each other at the free ends of said arms and are adapted to swingably support a yoke 85 or clevis 17. The clevis comprises spaced side members connected together near one end and having eyes 18 formed at their free ends, the eyes being provided with alined apertures having their outer ends oppositely bevelled 90 to form seats 19, as clearly shown in Figs. 3 and 4.

75 The trunnions 16 are initially provided with concave outer ends 20 and by bending or flexing the arms 4 of the handle member inwardly and the side members of the clevis outwardly, the said eyes 18 of the latter may be assembled upon the trunnions, the parts then bent to normal positions, when the concave 95 surfaces then facilitate the peening of the 100

ends of the trunnions over to fit, as at 21, within the seats 19 to hold the parts in operative relation to each other with the outer ends of the trunnions substantially flush with the outer faces of the eyes 18 (see Fig. 3). Thus, the peening can easily be done while the trunnions are cold.

The side members of the clevis are connected together adjacent to the outer ends thereof and, in the present example, one side member is extended and formed into an eye 22 to which is flexibly connected a chain hook 23 for the purpose of engaging the terminal link or other portion of the chain, as indicated at 24. On that side member of the clevis 17, having the eye 22 formed thereon, is provided an enlargement 25, preferably formed integrally therewith and having a pair of spaced fingers 26 extending from the same. These fingers, like the upper pair of fingers 14 of the hook 13, are formed with concaved surfaces for the reception of the links of the chain and are slightly curved downwardly throughout their lengths to retain the chain in engagement thereon. The fingers 26 are arranged at right angles to the clevis and project from the side member thereof, the free ends of the fingers extending toward the operating end of the handle and extending out from the clevis so as to be readily engaged by one of the links of the chain 15.

The implement has been illustrated in Fig. 1, as in the position for use in binding a chain on a load of logs or the like to hold the latter tightly bound together, as upon a car, truck or the like. When thus used the chain 15 is brought around the logs with the upper end 15 thereof passing downwardly as shown and the lower end passing upwardly, in order that the implement may be located on the side portion of the pile to facilitate the manipulation of the lever 1 while standing upon the ground and in order that the same may be readily released with safety to the operator when unloading the logs or the like. In binding a load the lower hook 23 is engaged in the terminal or other link of the lower end 24 of the chain and, by straightening out the implement in an obvious manner, the upper fingers 14 may be engaged with one of the links of the upper end 15. By pulling down upon the handle it will be seen that the points of engagement are brought towards each other when a free link may be engaged with the lower fingers 26 and a direct connection is effected between the two end portions of the chain and the lever may be swung, after the fingers 14 are detached from the chain, to move the latter upwardly to reach a high point and be again engaged in another link to draw the latter downwardly in the same manner.

It will be observed that the upper fingers 14, the lower fingers 26 and the hook 23 are all in substantial vertical alignment, when

used as illustrated, so that the chain may pass straight around the pile of logs or the like, and with the additional advantage that the free links of the upper end 15 of the chain are brought directly to the temporary holding fingers 26 without the necessity for crossing the chain at any point. Another advantage lies in the fact that the chain holding means are all located at one side of the operating handle so that the latter may be manipulated without any interference by the chain and a full swing of the handle may be obtained. The releasing operation may be accomplished by extending the implement to engage the fingers 14 with the chain and drawing the lever down sufficiently to release the chain from the fingers 26 and then detaching the fingers 14.

Obviously the present invention is not restricted to the particular embodiment thereof herein shown and described. Moreover, it is not indispensable that all the features of the invention be used conjointly, since they may be employed advantageously in various combinations and subcombinations.

What is claimed is:

1. An implement for binding loads comprising, in combination, an operating lever having a bifurcated end to provide spaced arms; integral, outstanding trunnions formed on the ends of the arms; a clevis pivotally mounted on said trunnions; spaced fingers formed integrally on one side of the clevis and extending transversely to the clevis; a hook connected to the free end of the clevis; a pull bar pivoted between the arms in spaced relation to the trunnions; a hook swivelled on the free end of the bar; and spaced fingers formed integrally on the hook and extending laterally from one side thereof.

2. An implement for binding loads comprising, in combination, an operating lever having its active end angularly formed and bifurcated to provide spaced arms; outstanding, aligned trunnions formed integrally on the outer faces near the ends of the arms, each trunnion having its end wall initially concaved; a clevis having spaced sides straddling said arms and provided with terminal eyes for the reception of the trunnions, said eyes having bevelled, annular seats to permit the concaved ends of the trunnions to be peened over thereinto; a lower chain hook flexibly connected to one end of the clevis; lower chain engaging fingers formed on one side of the clevis and extending toward the free end of the lever; a pull bar pivoted between the spaced arms near their inner ends; an upper chain hook swivelled to the free end of the bar and having spaced fingers extending from one side thereof and normally at right angles to the lower fingers when in operation.

3. An implement for binding loads comprising, in combination, an operating lever having a bifurcated active end; a pull bar

pivoted in the bifurcation near the inner end thereof; an upper chain hook swivelled to the free end of the pull bar and having spaced, laterally-extending fingers to temporarily engage the links of an upper chain end; a
5 depending clevis pivoted to the bifurcated end of the lever and having spaced fingers parallel to the lever to temporarily engage the links of said chain end when the lever is depressed; and a hook flexibly connected to the lower end of the clevis for connection to the lower chain end and to act as a fulcrum for the lever.

4. A load binder comprising, in combination, a hand lever; a clevis pivoted to the active end of the lever; a lower hook flexibly connected to the free end of the clevis and adapted to engage a lower chain end; a pull bar pivoted to the lever near the clevis; an upper hook swivelled to the free end of said bar; spaced, lateral fingers carried by the upper hook to engage the links of an upper chain end and draw the same down when the free end of the lever is depressed; and spaced fingers formed on the clevis adjacent to the pivots and extending parallel to and at one side of the lever to engage the links of the upper chain end when the same are drawn downwardly.

30 In testimony, that I claim the foregoing as my own, I have hereto affixed my signature.

LEO HAUBERT.
